UNITED STATES PATENT OFFICE.

AUGUST C. DITTRICH, OF CHICAGO, ILLINOIS.

TIME CONTROL FOR SOUND-REPRODUCING MECHANISM.

1,337,759.

Specification of Letters Patent. Patented Apr. 20, 1920.

Application filed December 7, 1918. Serial No. 235,684.

To all whom it may concern:

Be it known that I, AUGUST C. DITTRICH, a citizen of the United States, residing at Chicago, in the county of Cook and State of Illinois, have invented certain new and useful Improvements in Time Control for Sound-Reproducing Mechanism, of which the following is a specification.

This invention relates to means for automatically starting a sound reproducing mechanism at a predetermined time.

Among the objects of this invention is to provide means whereby one may effect the automatic starting of a sound reproducing mechanism at any predetermined time desired, thus enabling one to be pleasantly awakened in the morning by the playing of his favorite phonograph record instead of being rudely awakened by the ordinary terrifying alarm; further to so construct and apply such means that the normal operation of the sound reproducing mechanism and its parts, unhampered by the automatic starting means, may be instantly had when desired; further to provide releasing means that will be quick and positive in its action, and that can be quickly and easily connected up with or disconnected from a motor, clock or the like; further to arrange the motor, clock or the like on a door in the cabinet in such manner that the simple shutting of the door will connect the parts when properly arranged; further to provide a flexible detent strip which when flexed will hold the starting means inoperative, and when unflexed will release the starting means; further to provide novel means for flexing the detent strip; further the provision of such automatic starting means that will be more simple, economical and efficacious than heretofore known, and can be sold at a price within the reach of all, and be easily applied to any of the phonographs or the like in use in so many homes; and such further objects and advantages and capabilities as will later more fully appear.

My invention further resides in the combination, construction and arrangement of parts illustrated in the accompanying draw-

ings, and while I have shown therein a preferred embodiment, I desire it to be understood that the same is susceptible of modification and change without departing from the spirit of my invention.

In the drawings:

Fig. 1 is a perspective view of the upper portion of a phonograph and cabinet embodying my invention.

Fig. 2 is a fragmentary vertical sectional view taken laterally through the cabinet and showing the releasing mechanism as connected with the starting lever and clock.

Fig. 3 is a fragmentary plan view of a corner of the phonograph showing the starting lever and post mechanism.

Fig. 4 is a fragmentary perspective view showing the post and connected spring.

Fig. 5 is a perspective detail view of the flexible detent strip and associated parts.

Fig. 6 is a vertical sectional view taken on a plane passing through the detent strip adjacent the flexing crank and showing the door supporting the clock and standing partially open.

Fig. 7 is a fragmentary perspective view of a corner of the cabinet showing the slotted post receiving plate slightly removed from the corner of the cabinet.

Referring to the drawings: 1 designates the ordinary phonograph, Victrola, or the like, used in most homes, and carrying on its upper surface the rotatable plate 2, upon which is mounted the disk 3, contacting with which in the usual manner is the pin 4 connected with the sound conveying tube 5. Projecting from beneath the supporting plate 2 at one corner of the cabinet is the starting lever 6 provided with a perforation or other suitable depression 7, within which engages the downwardly projecting end 8 of the hook 9 formed upon the upper end of the post 10. This post is slidably mounted in an opening 11 in the corner of the cabinet, and with which opening 11 registers the opening 12 formed in the plate 13, secured in appropriate position on the top of the cabinet. The plate 13 is provided with slots 14 and 15 formed preferably ninety degrees

apart. The corner of the cabinet, as shown in Fig. 7, is cut out to form the opening 16, which also is preferably a quarter of a circle whereby its sides will fall below the outside 5 of the slots 14 and 15.

The post 10 has formed just below the hook 9 the cam 17, and below the cam the notch 18, forming the shoulder 19. Upon the lower end of the post 10 is a pin 20 extending through the aperture 21 of the plate spring 22, which at its opposite end is secured by screws or the like through the apertures 23 to the under side of the cabinet top. The spring 22 normally tends to hold 10 the post 10 in elevated position.

Referring more particularly to Figs. 2 and 5 and 6, it will be seen that I have also provided the flexible detent strip 24 extending beneath the cabinet top, preferably at 20 right angles to the spring 22. This detent strip is fixed by means of a screw or the like 25 to the under side of the cabinet top, and is provided adjacent its free end with a notch 26, which is of sufficient size to permit 25 the post 10 to move up and down therethrough when registering with the circumference of the post. Also secured to the under side of the cabinet top are the spaced apart keepers 27 through which the detent 30 strip 24 may slide when flexed between the screw 25 and the nearest adjacent keeper 27. As will be seen in Fig. 5, the notch 26 forms the shoulder 28 which, when the flexible strip 24 is flexed as shown in Fig. 2, 35 will engage the shoulder 19 of the post 10 when the post 10 has been suitably depressed to bring the shoulder 19 just below the shoulder 28 prior to flexing of the strip 24.

As a convenient means for flexing the 40 strip 24, I have shown the crank 29 pivoted at one end in an aperture in the cabinet wall and at the other end in a suitable bearing, staple, or the like, 30. Upon the outer end of the crank 29, which outer end projects 45 through the cabinet wall, there is formed a suitable finger piece 31 by means of which the crank 29 may be rotated as desired. Associated with the crank 29 and suitably connected with the cabinet wall is 50 the spring 32 normally tending to hold the crank 29 in elevated position, that is, against the under face of the cabinet top.

Formed upon the lower face of the detent strip 24 and adjacent the crank arm 29 is 55 the hook-like projection 33 which, as clearly seen in Fig. 6, is open at one side whereby when the detent strip 24 is flexed the hook 34 may be readily engaged therewith to hold said strip in flexed position. Any 60 form of alarm clock is designated by 35, from which the bell has been removed and the hammer supplanted by the hook 34. This clock is mounted in any desirable manner upon the door 36, so that as the door is

opened the clock will swing therewith, and 65 when the door is closed, the face of the clock appears through an opening in the door. From Fig. 6, it will be seen that when the strip 24 is flexed and the door swung shut, the hook 34 will readily pass over the shoulder 70 of the hook 33 to hold the strip 24 in the position shown in dotted lines in Fig. 6 and in solid lines in Fig. 2.

From the above it will be seen that in the 75 operation of my improved apparatus the parts being assumed to be in released position, the starting lever 6 will be swung toward the post 10 and the post depressed to bring the projection 8 of the hook 9 to take into the aperture or depression 7 of the 80 starting lever, whereby to hold the same against accidental movement into starting position. The post 10 will be held manually in such depressed position and the handle 31 of the crank 29 rotated to flex the detent 85 strip 24, whereby the shoulder 28 is carried into contact with the shoulder 19, thus holding the post 10 in depressed position. The alarm of the clock 35 having been previously set to the desired time, the door 36 90 is then swung shut to bring the hook 34 over the hook 33 as described above, and the crank released and returned to original position under the influence of spring 32, thus setting the parts in position to be released 95 at the predetermined hour.

At the predetermined hour the alarm will operate and carry the hook 34 out of engagement with the projection of the hook 33, thus permitting the flexed detent strip 100 24 to straighten, which carries the shoulder 28 clear of the shoulder 19, and permits the post 10 to rise under action of the spring 22. As the post rises the upper edge of the cam 17 will engage the starting lever 6 and 105 push the same sidewise a sufficient distance to start the sound reproducing mechanism of the phonograph or the like in operation.

Should it be desired to use the phonograph in its normal manner unhampered by 110 the starting mechanism, the post 10 may be depressed and rotated to swing the cam 17 through the opening 16 from the slot 14 to the slot 15 when the post is released and the cam rises through the slot 15 under action 115 of the spring 22. As is obvious, this will carry the cam 17 and hook 9 away from the starting lever 6, whereby the lever may operate normally unhampered by the automatic starting mechanism.

Having now described my invention, I claim:

1. In combination with sound reproducing mechanism, a rotatable table, a flexible strip attached to the sound reproducing mechanism, time controlled mechanism for holding said strip flexed, and means operably connecting said strip and said table 125

- whereby upon release of said strip at a pre-determined time said table will be released for rotation.
2. In combination a cabinet, sound reproducing mechanism, a door in said cabinet, an alarm clock mounted on said door for movement therewith, means in said cabinet capable of being released to automatically start said mechanism, and means for holding said first mentioned means in such position that the closing of said door will connect the alarm mechanism of the clock with said first mentioned means to release the same to start the said mechanism at a predetermined time.
3. In combination with sound reproducing mechanism, a rotatable table, a spring pressed movable member for effecting the release of said table to permit its rotation, a flexible detent strip for controlling said member, and time controlled means operable at a predetermined time to release said detent strip when flexed, whereby said member may move to release said table.
4. In combination with sound reproducing mechanism, a rotatable table, a spring pressed movable member for effecting the release of said table to permit its rotation, a flexible detent strip for controlling said member, manually operable means for flexing said strip, and time controlled means operable at a predetermined time to release said detent strip when flexed, whereby said member may move and effect the release of said table.
5. In combination with sound reproducing mechanism, a rotatable table, a spring pressed movable member for effecting the release of said table to permit its rotation, a flexible strip for controlling said member, means for flexing said strip comprising a hand operated crank, and time controlled means operable at a predetermined time to release said detent strip when flexed, whereby said member may move and the release of said table be effected.
6. In combination a cabinet adapted to accommodate sound reproducing mechanism, an apertured plate on the top wall of said cabinet, said plate having spaced radial slots therein, a post mounted for longitudinal movement in said plate with a cam movable through either of the said slots, said cam being adapted to actuate the starting lever of said mechanism upon movement of said post in one direction, a spring for moving said post, said cam being in position to engage the lever when in one of said slots and to clear the same when in the other.
7. In combination a cabinet adapted to accommodate sound reproducing mechanism, an apertured plate on the top wall of said cabinet, said plate having spaced radial slots therein, a post mounted for longitudinal movement in said plate with a cam movable through either of the said slots, said cam being adapted to actuate the starting lever of said mechanism upon movement of said post in one direction, a spring for moving said post, said cam being in position to engage the lever when in one of said slots and to clear the same when in the other.
8. In combination a cabinet, sound reproducing mechanism having a starting lever, a post having means for holding said lever in inoperative position when depressed and for moving the same to operative position when moved longitudinally, a spring for normally moving said post to actuate said lever, locking means for holding said post depressed, and time controlled means for releasing said locking means to start said device at a predetermined time.
9. In combination a cabinet, sound reproducing mechanism having a starting lever, a post having means for holding said lever in inoperative position when depressed and for moving the same to operative position when moved longitudinally, a spring for normally moving said post to actuate said lever, locking means for holding said post depressed, time controlled means for releasing said locking means to start said device at a predetermined time, and means permitting said post to be rotated to a position where its movement longitudinally will not affect said lever.
10. In a device of the class described, a longitudinally movable member having a hook on one end adapted to hold the starting lever of a sound reproducing device in inoperative position when said member is depressed, said member also having a cam adapted to actuate said lever upon movement of said member, a shoulder on said member, a spring for moving said member, means engaging said shoulder to hold said member depressed and means to release the same at a predetermined time to start said device.
11. In combination with sound reproducing mechanism, a turn table, a longitudinally movable member adapted to move the starting lever of said turn table into operative position, a flexible strip adapted when held flexed to hold said member inoperative with relation to said lever, and time controlled means to release said strip to permit it to unflex whereby said member may actuate said starting lever.
12. In combination with sound reproducing mechanism, a cabinet, a turn table on said cabinet, means for holding said turn table against rotation, a post slidably mounted in said cabinet, a flexible strip adapted

when flexed to hold said post depressed, time controlled means to hold said strip flexed and at a predetermined time to release it whereby said post will move upwardly, said 5 post and said turn table holding means being so associated that upward movement of the post will move said holding means into position to release said turn table.

13. An automatic starting attachment for 10 sound reproducing devices comprising a longitudinally movable member adapted to move the starting lever of said device to operative position upon movement of said member, a spring normally tending to move 15 said member, a flexible detent strip adapted to hold said member against movement when flexed and release it when unflexed, and time controlled means for releasing said strip from flexed position to permit it to 20 straighten and release said member to start the sound reproducing device at a predetermined time.

14. In a device of the class described, 25 sound reproducing mechanism, a cabinet for the same, an alarm clock, and means connecting said clock with said mechanism to automatically start the latter at a predetermined time upon release of the alarm, said means including a post slidably mounted 30 in said cabinet, means associated with said post for releasing the phonograph for operation upon upward movement of the post, and resilient means for normally causing the post to move upwardly when released by 35 the alarm mechanism of said clock.

15. In an attachment for sound reproducing mechanism, a longitudinally movable post having a cam portion adapted to move the starting lever of said mechanism into 40 operative position when said post is elevated, and means for causing the elevation of said post at a predetermined time to start said mechanism, said means comprising a flexible detent strip for holding said post 45 depressed when said strip is flexed, a spring normally tending to elevate said post, and time controlled means for permitting the strip to straighten to release said post.

16. In apparatus of the class described, 50 sound reproducing mechanism having a starting lever, and means for automatically starting the same at a predetermined time, said means comprising a longitudinally movable post having means thereon for moving said lever to starting position as said post is elevated, a spring normally tending to hold said post elevated, and a time controlled flexible detent strip adapted to hold said post depressed when said strip is 55 flexed and to release the post when said strip is unflexed at a predetermined time.

17. In apparatus of the class described, 60 sound reproducing mechanism having a starting lever, a movable post adjacent said

lever, means on said post for moving said 65 lever into starting position upon movement of the post, a spring normally tending to move said post to operate said lever, means for holding said post away from said lever, said last mentioned means comprising a 70 flexed detent strip, and time controlled means for releasing said flexed strip to release said post and move said lever to start said sound reproducing mechanism.

18. In apparatus of the class described, a 75 cabinet, sound reproducing mechanism, a starting lever for the same, a post movably mounted in said cabinet adjacent said starting lever, a spring normally tending to hold said post in elevated position, said post having means to push the starting lever side- 80 wise when moved upwardly by said spring, a flexible detent strip having means for holding said post depressed when the strip is flexed and for releasing the same when the 85 strip is unflexed, means for flexing the strip, means for releasably holding it flexed, and time controlled means for releasing the flexed strip at a predetermined time to permit said post to move said starting lever into 90 operative position.

19. In apparatus of the class described, 95 sound reproducing mechanism, a starting lever for the same, a cabinet, a post movably mounted in a wall of the cabinet and having a projection on its upper end adapted to engage with an aperture in the starting lever when said lever is in inoperative position and said post depressed, said post also having a shoulder and a cam, a spring normally 100 tending to hold said post in elevated position, a flexible detent strip fixed at one end and slidably mounted at the other with relation to said cabinet, means for flexing said strip, a time controlled motor, means for releasably connecting said strip when flexed with said motor to hold it in flexed position, and means on said strip engaging said post shoulder when the post is depressed and the strip flexed, said last mentioned means being 105 moved to position to release said post when the flexed strip is released and permitted to straighten whereby to raise said projection away from the lever and permit the cam under the action of said spring to move said 110 lever into operative position to start said sound reproducing mechanism.

20. In a sound reproducing instrument 115 comprising sound reproducing mechanism, a starting lever for the same, and a cabinet, in 120 combination a post movably mounted in the cabinet wall adjacent said lever, a cam and a shoulder on said post, a spring normally tending to move said post to push said cam toward said lever, a flexible detent strip 125 fixed at one end to said cabinet, a keeper through which the other end of said strip is adapted to slide when said strip is flexed

between its fixed end and said keeper, means 5 for flexing said strip, means for releasably connecting said strip when flexed to the alarm mechanism of a clock, and means on the free end of said strip adapted to take over the shoulder on the post when the strip is flexed to hold the post in retracted position and to free the same when the strip is unflexed, whereby when said flexed strip is 10 released by the alarm mechanism said post is

in turn released and the starting lever pushed into operative position by said cam.

In witness whereof I hereunto subscribe my name to this specification in the presence of two witnesses.

AUGUST C. DITTRICH.
